TAPER ATTACHMENT FOR LATHES

Frank E. Cheever, Springfield, Vt., assignor to
 Jones & Lamson Machine Company, Springfield, Vt., a corporation of Vermont

Application July 11, 1939, Serial No. 283,852

11 Claims. (Cl. 82—17)

It has been customary when taper turning on a lathe has been desired, to disconnect the usual carriage feed and operatively connect the tool carrier to a follower guided for feed motion by a templet bar at the back of the machine angularly adjustable to the longitudinal axis of the lathe bed to determine the angle of taper, the templet being held against traversing movement with the traversing carriage on which the tool carrier is mounted. The disconnection or connection of the hand or automatic feed and the connection or disconnection of the tool carrier to the follower have previously been done as separate operations, the operative connection or disconnection of the tool carrier to the follower requiring that the operator go to the rear of the machine or reach across from the front if the distance is not too great. These operations being independent for connecting or disconnecting the two types of feed, there is always the possibility that the operator may make one connection without releasing the other, which might result in serious damage, if it were attempted to operate the machine under these conditions.

One object of the present invention, therefore, is to provide a single actuating means by which the connections to both controls are operated together and in the proper relationship to each other and by which both may be accomplished by the operator without requiring that he go to the rear of the machine.

A further object is to provide mechanism by which combined straight and taper turning may be effected with the great accuracy which is required for repetitive work and in an expeditious and convenient manner.

For a more complete understanding of this invention reference may be had to the accompanying drawings in which

Figure 1 is a fragmentary top plan of the tool carriage portion of a lathe embodying the invention and with the taper turning mechanism inoperative.

Figure 2 is a rear elevation of the same.

Figures 3, 4, 6 and 7 are detail sections on the correspondingly numbered section lines of Figure 1, Figure 3 being shown also as taken on the section line 3—3 of Figure 6.

Figure 5 is a detail section on line 5—5 of Figure 4.

Figure 8 is a view similar to a portion of Figure 6, but showing the parts in taper turning condition.

Figure 9 is a view similar to a portion of Figure 3, but showing a modification.

Figure 10 is a somewhat diagrammatic view partly in top plan and partly broken away and in section showing the relationship between the tool and work for opposite directions of traverse, showing the modification of Figure 9.

Referring first to Figure 6, at 1 is shown a portion of the bed of a lathe having ways 2 thereon on which is slidably mounted guides 3 of a traversing carriage 4, it being understood that this carriage traverses lengthwise of the ways 2 in the usual manner. Said traverse may be effected by rotation of a pinion 5 projecting from a gear casing 6 carried by the carriage and meshing with teeth of a rack bar 7 secured to the bed of the machine in the well known manner. Slidable on ways 10 (see Figure 2) transverse to the traversing direction of the carriage is a tool carrier 11. This carrier 11 may be fed relative to the carriage when desired, wholly independent of the traverse of the carriage, or where it is desired to produce taper turning, means are provided for effecting a feed motion of the carrier proportional to and controlled from the traverse of the carriage.

According to this invention means is provided by which at any selected of a plurality of definite traverse positions of the carriage, the taper feed mechanism may be thrown into action, and where the normal feed of the carrier independent of the motion of the carriage is not operated during that portion of the traverse in which the taper turning attachment is out of operation, the turning is straight. Thus combinations of straight and taper turning may be readily effected by throwing in or out the taper turning device at selected points in the carriage traverse.

As shown the feed motion of the tool carrier may be produced independently of the traverse of the carriage by the rotation of a feed screw 15 journaled in the carrier and axially fixed with relation thereto, by the rotation of the hand feed wheel 16. It will be noted that the hub 17 of this wheel (see Figure 7) is mounted on a reduced extremity 18 of the feed shaft, this reduced extremity being journaled in the end plate 19 of the carrier which butts against the shoulder 20 on the feed screw formed by the reduction in diameter of its outer end. This feed screw 15 is threaded through an elongated nut member 21 and when this nut member is held against axial movement relative to the carriage 4, an axial motion of the screw 15 by reason of its turning will produce a motion in the same direction of feed or retraction to the tool carrier 11. Such holding of the nut 21 against axial motion

relative to the carriage 4 may be produced by tightening against its outer end a clamp collar 22. As shown best in Figure 4, this clamp collar is split and one portion as 23 has journaled therein a screw 24 which is threaded into a nut 25 adjustably secured in the opposite portion 26. The nut 25 is externally threaded for engagement with the internal threads in a bore 27 in the portion 26, so that it may be adjusted axially therein by its turning, and its outer end is shown as cut away to form a polygonal head 28 which may be engaged with a suitable wrench for that purpose. When adjusted to the desired position, it may be held against turning as by the set screw 29. On the opposite side portion 23 of the split collar, the screw 24 has a head 30 which bears against the outer face of the portion 23. By turning the screw 24 it is thus evident that the collar 22 may be expanded or contracted to release or grip the nut 21. This collar 22 is held against axial motion, and for this purpose it is shown in Figures 2 and 4 as provided with an end flange 32 which may be secured as by the screws at 33 to a member secured to the rear side face of the carriage 4. When the clamping collar is released, the nut 21 is free to be moved axially by rotation of the screw 15, for a limited distance, determined by the spacing of opposite ends of the nut 21 from a sleeve 35 (see Figure 7) in which the screw 15 is journaled and from a tubular casing 36 which houses the rear end of the screw 15. These spaces are shown at 37 and 38, respectively.

35 The taper turning attachment is constructed to move the nut 21 axially in accordance with the traversing motion of the carriage 4 and for this purpose it has a boss 40 depending therefrom on which is rockably mounted a cam follower 41 (see Figure 1). This cam follower is in the form of a rectangular block having a hole to rockably receive the boss 40, this block riding between upwardly extending side wall members 43 and 44 of a former cam 45. This former cam is shown as adjustably secured to a bracket member 46, the adjustability permitting it to be adjusted to the desired angle to the direction of traverse to control the amount of taper. As shown it is securable at one end through a bolt and slot connection at 50, and its opposite end may be provided with segmental gear teeth 51 for engagement with an adjusting pinion 52 which may have a squared hub portion 53 by which it may be turned. This cam may be fulcrumed adjacent to its center to the carriage 4 as by the pivot bolt 55 shown best in Figure 3. The bracket 46 is slidably mounted with reference to the carriage 4 in the direction of traverse of the carriage, this carriage being provided with an extension 60 having the spaced depending webs 62 to the lower edges of which are secured the retaining bars 63 which support the side edge portions of the bracket 46. A gib 64 may be employed to afford a sliding fit to the bracket 46 with reference to the extension 60. This bracket 46 has a downward extension 65 having an opening for the slidable reception of a stationary bar 68 which extends along the back of the machine in spaced parallel relation to the ways 2 and is suitably secured. This bar 68 is provided at spaced intervals with notches 70 at its under side and into any of these notches may be projected when desired a locking finger 71. This locking finger is keyed to a rock shaft 72 journaled in the extension 65 and between forks 74 projecting from the

portion 63. When the finger 71 is in its lifted position in engagement in any selected of the notches 70, the bracket 46 is held stationary during the traverse of the carriage, and as the carriage carries with it the nut 21 and the follower 41, while the former cam 45 is held stationary with the bracket 46, any angularity of this former bar will cause a corresponding axial motion to the nut 21. As this nut is held from rotation by the engagement of its boss 40 in the block 41 and this block 41 between the wall members 43 and 44, this will result in axial motion of the feed shaft 15 and provided it is not rotated, a corresponding in or out feed motion of the tool carrier 11. To permit this axial motion of the nut 21, the clamp 22 is released therefrom, and provision is made in accordance with this invention whereby the clamping of the bracket 46 against traversing motion will release the clamping collar 22 and the clamping of the collar 22 will cause the release of the bracket 46 so that it may traverse with the carriage. To this end the rock shaft 72 is slidably mounted through a forked extension 74 of the member 60 and has keyed thereto between the forks an arm 80 connected by a link 81 to one arm 82 of a bell crank lever 83. This bell crank lever 83 is keyed to the clamp-actuating shaft 24 and is provided with an upstanding arm 85 to which is pivoted the rear end of an actuating bar 86. This actuating bar extends along one side of the tool carrier 11 and at its forward end is pivoted as at 87 to an actuating handle 88 fulcrumed at 89 on the forward face of the carriage 11.

In the position of the parts shown in Figure 3, with the handle 88 in its forward position, the bell crank lever 83 is in such angular position as to clamp the collar 38 and hold the nut 21 against axial motion relative to the carriage, and the finger 71 is out of engagement with the stationary bar 68 so that the bracket 46 is free to move with the carriage during its traverse. Under these conditions and assuming the feed shaft 15 not rotating, there is no feed of the tool carrier during traverse, so that straight turning is accomplished, although, if desired, a feed motion may be imparted by turning the feed wheel 16. By moving the handle 88 into the dotted line position of Figure 6, however, the rod 86 is pushed rearwardly, rocking the bell crank lever 83 as shown in Figure 8, and releasing the clamping engagement of the collar 22 against the nut 21 while bringing the finger 71 up into locking engagement with the stationary bar 68. The bracket 46 is now held from motion with the traverse of the carriage 4, and this traverse thus produces through the engagement of the follower 41 with the now stationary former cam, a feed motion of the tool carrier coordinated with the traverse of the carriage thus to turn taper to an amount depending on the angular adjustment of the former cam, the release of the clamping collar 22 permitting such action to take place with an axial motion of the screw 15 unaccompanied by a rotary motion. During this traverse, the extension 60 of the carriage travels along the rock shaft 72 which is held locked to the stationary bar 68.

It will thus be seen that it is quite unnecessary for the operator to go around in back of or reach across the machine in order to render the taper turning attachment operative or inoperative, and that it is also unnecessary for him by a separate operation to render the screw feed means operative or inoperative. Both such actions are accomplished by a single throw of the handle 88

and in a manner which insures only one of these feed mechanisms being operative at any one time. This would be of particular importance in any case where a power operation of the feed screw is provided for, as is commonly done. As this is a common practice, however, it is not illustrated herein as per se it forms no part of the present invention.

In Figures 2 and 3 the finger 71 fits closely in the notches 70. In Figure 9 the notches 71' are shown as of greater width than the thickness of the finger 71 thus providing a limited lost motion which is taken up at the start of traverse so that the tool path is slightly different in opposite directions of traverse. Where the direction of active traverse between the tool and the work is from the smaller to the larger diameter portions, as shown by arrow A in Figure 10, the finger 71 is held against one or the other side of the slot 71 depending on the traverse direction, such that on the return direction of traverse the tool lags behind its cutting position so that its edge has a transverse position corresponding to a larger diameter portion of the work than was cut on the working traverse. It is therefore relieved, out of contact with the cut surface, during the return traverse and cannot score the cut surface.

From the foregoing description of an embodiment of this invention, it should be evident to those skilled in the art that various changes and modifications might be made without departing from the spirit or scope of this invention as defined by the appended claims.

35 1. I claim:

1. In a machine of the class described provided with a support having ways, a carriage movable along said ways, a tool carrier movable on said carriage transverse to the direction of motion of said carriage, means controlled by motion of said carriage for moving said tool carrier relative to said carriage, means for operatively connecting and disconnecting said controlled means, other means for producing motion of said tool carrier relative to said carriage, a movable control member at the front of the machine, and connections from said movable member to said connecting and disconnecting means and to said other means causing said connecting and disconnecting means 50 to connect said controlled means and render inoperative said other means in one position of said member and in another position of said member to disconnect said controlled means and render operative said other means.

55 2. In a lathe having a traversing carriage, a tool carrier movable transverse to the direction of motion of said carriage, a feed screw for said tool carrier, a bracket carried by said carriage for relative movement thereto parallel to the direction of traverse, a former cam angularly adjustable on said bracket, a follower for said cam, said lathe including means for operatively connecting said follower to said tool carrier, means for holding said bracket stationary while the traverse of said carriage continues to cause said cam and follower to move and control said tool carrier, means for rendering said feed screw operative or inoperative by its turning to move said tool carrier, a movable actuating member, and means connecting said actuating member to said bracket-holding means and said rendering means causing said bracket to be held and said screw inoperative to move said carriage by its turning in one position of said member, and 75 said bracket to be released and said screw to be

operative by its turning to move said carrier in another position of said member.

3. A lathe having a bed, a traversing carriage movable on said bed, a tool carrier movable transverse to the traversing direction, a feed screw 5 mounted for rotation but axially fixed on said carrier, a nut threaded on said screw, a follower carried by said nut, a bracket carried on said carriage for movement relative thereto in the direction of traverse, a stationary bar along 10 which said bracket is movable, a former cam angularly adjustable relative to the direction of motion of said carrier and in controlling relation to said follower, means for clamping or releasing said bracket relative to said bar, means for 15 clamping or releasing said nut for motion relative to said carriage, a member movably mounted on said carriage, and operative connections from said member to said two clamping and releasing means holding the one clamped and the other 20 released in one position of said member and the one released and the other clamped in another position of said member.

4. A lathe having a bed, a traversing carriage movable on said bed, a tool carrier movable 25 transverse to the traversing direction, a feed screw mounted for rotation but axially fixed on said carrier, a nut threaded on said screw, a follower carried by said nut, a bracket carried at the back of said bed on said carriage for movement relative thereto in the direction of traverse, a stationary bar along which said bracket is movable, a former cam angularly adjustable 30 relative to the direction of motion of said carrier and in controlling relation to said follower, means for clamping or releasing said bracket relative to said bar, means for clamping or releasing said nut for motion relative to said carriage, a member movably mounted at the front side of said bed on said carriage, and operative connections 35 from said member to said two clamping and releasing means holding the one clamped and the other 40 released in one position of said member and the one released and the other clamped in another position of said member.

5. A lathe having a bed, a traversing carriage movable on said bed, a tool carrier movable transverse to the traversing direction, a feed screw 45 mounted for rotation but axially fixed on said carrier, a nut threaded on said screw, a follower carried by said nut, a bracket carried on said carriage for movement relative thereto in the direction of traverse, a stationary bar along which said bracket is movable, a former cam angularly adjustable relative to the direction 55 of motion of said carrier and in controlling relation to said follower, said stationary bar having notches spaced therealong, a locking finger movable into and out of any selected notch to hold said bracket stationary during continued traverse 60 of said carriage, a clamp collar surrounding said nut and carried by said carriage, connections between said clamp collar and said finger holding said collar unclamped when said finger is in one of said notches, and holding said finger retracted 65 when said clamp collar is in clamped condition, and means for actuating said connections from one to the other of its conditions.

6. A lathe having a bed, a traversing carriage movable on said bed, a tool carrier movable transverse to the traversing direction, a feed screw mounted for rotation but axially fixed on said carrier, a nut threaded on said screw, a follower carried by said nut, a bracket carried on said carriage for movement relative thereto in the 70 75

- direction of traverse, a stationary bar along which said bracket is movable, a former cam angularly adjustable relative to the direction of motion of said carrier and in controlling relation to said follower, said stationary bar having notches spaced therealong, a locking finger movable into and out of any selected notch to hold said bracket stationary during continued traverse of said carriage, a clamp collar surrounding said nut and carried by said carriage, connections between said clamp collar and said finger holding said collar unclamped when said finger is in one of said notches, and holding said finger retracted when said clamp collar is in clamped condition, and means for actuating said connections from one to the other of its conditions, said connections including a toggle which is made when said finger is in one of said notches and is broken when said clamping collar is clamped.
20. 7. In a lathe having a traversing carriage, a tool carrier on said carriage mounted for motion relative thereto transverse to the direction of traverse, a bracket carried by said carriage at the back of the machine for movement relative to said carriage in the direction of traverse, a former cam angularly adjustable with respect to said traverse direction carried by said bracket, a cam follower for said cam operatively connected to said carrier, and means for selectively locking or releasing said bracket in stationary position, a member movably mounted on the front part of said carriage, and operative connections from said member to said selective means.
35. 8. A lathe having a traversing carriage, a tool carrier on said carriage mounted for movement transverse to the line of traverse, a feed screw journaled for rotation in said carrier, a nut threaded on said screw, means holding said nut against rotation, a clamp carried by said carrier in clamping relation to said nut, a rock member, and means operatively connecting said rock member and clamp for closing or opening said clamp with relation to said nut on rocking of said rock member.
40. 9. A lathe having a bed, a traversing carriage movable on said bed, a tool carrier on said carriage movable transverse to said traverse, a bracket carried by said carriage for movement relative thereto in the traverse direction, a stationary member along which said carriage is movable, a former cam carried by said bracket and angularly adjustable relative to the direction of traverse of said carriage, operative connections from said former cam to said tool car-
- rier, and means actuatable to lock said bracket to said stationary member with a limited lost motion whereby said tool traverses a slightly different path relative to the work during traverse of said carriage in opposite directions.
10. 10. A lathe having a bed, a traversing carriage movable on said bed, a tool carrier movable transverse to the traversing direction, a feed screw mounted for rotation but axially fixed on said carrier, a nut threaded on said screw, a follower carried by said nut, a bracket carried on said carriage for movement relative thereto in the direction of traverse, a stationary bar along which said bracket is movable, a former cam angularly adjustable relative to the direction of motion of said carrier and in controlling relation to said follower, said stationary bar having notches spaced therealong, a locking finger of less thickness than the width of said notches movable into and out of any selected notch to hold said bracket stationary during continued traverse of said carriage and providing for lost motion between said bracket and carriage which is taken up at the start of traverse in each direction, a clamp collar surrounding said nut and carried by said carriage, connections between said clamp collar and said finger holding said collar unclamped when said finger is in one of said notches, and holding said finger retracted when said clamp collar is in clamped condition, and means for actuating said connections from one to the other of its conditions.
15. 11. In a machine of the class described provided with a support having ways, a carriage movable along said ways, a tool carrier movable on said carriage transverse to the direction of motion of said carriage, means controlled by motion of said carriage for moving said tool carrier relative to said carriage, means located at the back of the machine for operatively connecting and disconnecting said controlled means, other means for producing motion of said tool carrier relative to said carriage, a movable control member at the front of the machine, and connections from said movable member to said connecting and disconnecting means and to said other means causing said connecting and disconnecting means to connect said controlled means and render inoperative said other means in one position of said member and in another position of said member to disconnect said controlled means and render operative said other means.
20. 33. 45. 50. 55. FRANK E. CHEEVER. 55
